US0D1100795S

(12) **United States Design Patent** (10) Patent No.: **US D1,100,795 S**
(45) Date of Patent: ** Nov. 4, 2025

(54) **PERIMETER SENSOR HOUSING**(71) Applicant: **Waymo LLC**, Mountain View, CA (US)(72) Inventors: **YooJung Ahn**, Mountain View, CA (US); **Jared S. Gross**, Belmont, CA (US); **Thomas Southworth**, Royal Oak, MI (US); **Bernardo Mellado Medina**, San Francisco, CA (US)(73) Assignee: **Waymo LLC**, Mountain View, CA (US)(**) Term: **15 Years**(21) Appl. No.: **29/865,871**(22) Filed: **Aug. 17, 2022****Related U.S. Application Data**

(63) Continuation of application No. 29/744,120, filed on Jul. 27, 2020, now Pat. No. Des. 964,909, which is a continuation-in-part of application No. 29/724,655, filed on Feb. 18, 2020, now Pat. No. Des. 964,908, which is a continuation-in-part of application No. 29/688,902, filed on Apr. 25, 2019, now Pat. No. Des. 965,498.

(57) **CLAIM**

The ornamental design for a perimeter sensor housing as shown and described.

DESCRIPTION

FIG. 1 is a front perspective view of the claimed design for a perimeter sensor housing;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures illustrate portions of the perimeter sensor housing that form no part of the claimed design.
